UNITED STATES PATENT OFFICE.

FRANK YOKEL, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

LAMP-FIXTURE.

1,349,483.

Specification of Letters Patent. Patented Aug. 10, 1920.

Application filed February 19, 1917. Serial No. 149,441.

To all whom it may concern:

Be it known that I, FRANK YOKEL, a citizen of the United States, residing at Pittsburgh, in the county of Allegheny and State 5 of Pennsylvania, have invented certain new and useful Improvements in Lamp-Fixtures, of which the following is a specification.

My invention relates to lamp fixtures and 10 more particularly to electric lamp fixtures of that type which has a pivotally adjustable shade carrying a lamp within it.

The objects of the invention are to provide means of a simple and effective construction for supporting both the shade and lamp and enabling the shade to be pivotally connected to a suitable coupling or bracket, and also providing a conduit for the electric wire cord, all without requiring the 20 formation of a hole for the support of the wires through the body of the shade and without requiring the use of trunnions to carry the shade, while at the same time permitting the support and cord carrying 25 member to enter the shade at the rear face thereof, and the lamp to be supported with its axis extending parallel to the longer axis of the shade, and also enabling the exterior contour of the shade to be preserved un- 30 marred by the projection of the supporting means and enabling all parts of the supporting means for the shade and the lamp, with the exception of a small part of the shade clamping plate, to be inclosed within the 35 boundary of the shade, thereby increasing the sightliness of the fixture.

With these objects and others in view, my invention is embodied in preferable form in the construction hereinafter described and 40 illustrated in the accompanying drawing.

In these drawings,

Figure 1 is a rear view in elevation, partly broken away, of my improved lamp fixture and taken on the section line 1-1 of Fig. 2. 45 Fig. 2 is a horizontal section partly in plan.

Fig. 3 is a detail section on the line 3-3 of Fig. 1.

Fig. 4 is a detail front elevation of the 50 lock nut and part of the lamp bracket.

Referring to the drawings, 1 indicates the lamp shade which is of substantially semi-elliptical outline and hollow in form, and which is provided with a single opening 2

for the admission of the supporting means 55 for the shade and the lamp. This opening is formed in the rear face only of the shade and is preferably of semi-elliptical form. Extending through this opening is the main supporting means 2' having a threaded stem 60 3 projecting within the interior of the shade and which member is provided at its outer end with one element 4 of a ball and socket joint, the other element 5 of which forms part of the screw plug 6 which is adapted to 65 be engaged with a standard wall plate or bracket or other suitable means of support. 7 is an inner clamping nut adapted to lock the two elements together to hold the supporting member rigidly in adjusted position. The screw plug and the supporting member are tubular in form to permit the 70 passage therethrough of the lamp terminal cord 8.

Bearing against the shoulder 9 formed on 75 the supporting member is a flanged clamping plate 10 of semi-elliptical form, to conform to the shape of the opening 2, and the flange on the curved portion of which is adapted to bear against the rear face of the 80 shade and to take over a similarly curved flange 11 formed on the rear face of the shade and projected outwardly therefrom. The curved flange of the plate 10 is continued into a wider straight flange or lip 85 extending across the lower edge of the opening 2 and adapted to engage the adjacent border portions of the shade, as shown in Figs. 1 and 2.

On the threaded stem 3 within the lamp 90 shade is mounted a complementary clamping member 12 also consisting of a flanged semi-elliptical plate and which has the upper curved part thereof provided with a short flange bearing against the inner face 95 of the shade and has the lower straight edge thereof provided with a lip 13 which projects below the border of the shade and is adapted to take over the straight flange of the clamping member 10. Threaded on the 100 stem 3 and bearing against the clamping plate 12 is a lock nut 14 having recesses in its periphery adapted to be engaged by a suitable tool to enable the same to be secured against the plate 12 to clamp the shade between the two clamping members 10 and 12, 105 and thus hold the shade firmly on the supporting member.

The inner end of the stem 3 is flattened at 15 and such portion is adapted to be engaged by the inner apertured end of an arm 16 of a lamp carrying bracket, such flat portion serving to prevent the arm from turning. The arm 16 is held rigidly in place on the threaded stem by and between nuts 17. This bracket arm extends parallel to the longer axis of the lamp shade and at its end 10 is bent at right angles to form the arm 18, to the end of which the lamp socket 19 is secured. The lamp socket and the lamp 20 are thus projected longitudinally of the longer axis of the shade.

15 It will be seen that in this construction the lamp carrying bracket is entirely inclosed within the shade and that the only parts of the fixture which project outside of the shade are the pivoted part of the supporting member and the outer clamping plate 10, and the lower lip of the complementary clamping plate 12, whereby the contour of the shade is uninterrupted by projecting parts, and at the same time a very simple 25 construction for supporting both the shade and the lamp is provided.

What I claim is:—

1. A lamp fixture including a shade having a border opening in the rear face thereof, a lamp, exterior and interior shade clamping plates covering the opening, a combined shade and lamp supporting tubular member having a threaded stem portion extending through said clamping plates and 30 into the interior of the shade, locking means mounted on and coöperating with the threaded stem, and a lamp bracket secured to the stem and inclosed within the boundaries of the shade.
- 40 2. A lamp fixture including a shade formed with a border opening in the rear face thereof, a lamp, exterior and interior shade clamping plates covering said opening, a supporting member having its outer 45 end provided with a pivoting element and a threaded portion extending through said

clamping plates to the interior of the shade, a lock nut mounted on the threaded portion, and a lamp bracket secured to the supporting member and inclosed within the boundaries of the shade. 50

3. A lamp fixture including a shade having an opening in the rear face thereof, a combined shade and lamp supporting member extending through the shade opening, 55 said member having a threaded portion and a flattened portion, an exterior clamping plate on the supporting member, an interior adjustable clamping plate on the supporting member, locking means coöperating with the threaded portion, and an angular lamp bracket connected with the flattened portion 60 of the supporting member.

4. A lamp fixture having a shade, a border opening in the rear face of the shade, a 65 supporting member extending through said opening, shade clamping members engaging said shade and mounted on said member, said supporting member having a threaded stem extending into the interior of the shade, 70 and a lamp bracket mounted on the inner end of said stem.

5. A lamp fixture having a shade provided with an opening formed therein from the border upwardly in the rear face of the 75 shade, the edge of the shade being uninterrupted in contour except for said opening, said shade having a flange along the border of said opening, an exterior clamping plate conformed to the contour of the shade and 80 having a flange adapted to engage said shade flange, an interior shade clamping plate having a lip to engage said outer plate, a supporting member extending through said plates, and clamping and locking means for 85 said plates mounted on said member.

In testimony whereof I affix my signature in presence of two witnesses.

FRANK YOKEL.

Witnesses:
